UNITED STATES PATENT OFFICE.

HENRY C. ARWE, OF BROOKLYN, NEW YORK.

FILTER-BAG HOLDER.

1,408,491.

Specification of Letters Patent. Patented Mar. 7, 1922.

Application filed June 2, 1920. Serial No. 385,891.

To all whom it may concern:

Be it known that I, HENRY C. ARWE, a citizen of the United States, residing at Brooklyn, in the county of Kings and State 5 of New York, have invented certain new and useful Improvements in Filter-Bag Holders, of which the following is a specification.

This invention relates to filter bag holders 10 for coffee urns, and seeks to provide an efficient and practical device of this character having decided advantages over those now in use.

Filter bag holders have heretofore been 15 made both with and without bails or handles. When made without handles, it has been customary to employ a divided ring, provided with a coupling by means of which the ends may be united. Such a ring can 20 be readily threaded through a loop formed around the top of the filter bag. When made with bails or handles, it has heretofore been the practice to attach the ends of the bail permanently to the ring. With 25 such a construction, it is obviously impossible to thread the ring through a bag loop, and it is therefore necessary to fold the edge of the bag over the ring and then sew it in position. Owing to the inconvenience 30 of thus having to sew the bag in position on the ring, the object of the present invention is to provide a ring onto which a ready-formed bag may be easily slipped, such ring at the same time being equipped with a bail 35 or handle by means of which the bag may be conveniently lifted.

In order that my invention may be readily understood, reference is had to the accompanying drawing, forming part of this 40 specification, and in which:—

Figure 1 is a side elevation of my improved filter bag holder with the bag in position thereon;

Figure 2 is a plan view of the holder 45 alone, and

Figure 3 is a side elevation of the holder looking in a direction at right angles to Figure 1 and showing the method of assembling the bag and the holder.

50 Referring to the drawings in detail, my improved holder comprises a ring 1 which, as usual may be formed of stiff wire. This ring is not continuous, but is divided at one point so as to form a free end 2. This end 55 may be rigidly united with the other end of the ring, by means of a coupling 6. This

coupling is shown as in the nature of a double sleeve, one member of which is soldered or otherwise permanently attached to the ring and the other member of which 60 is open and adapted to receive the free end 2 of the ring. In Fig. 2 the parts are shown in full lines united and in dotted lines separated.

In order to conveniently lift the bag and 65 ring, I provide a bail or handle 4. This is permanently and preferably rigidly attached at one end to the ring as at 3, and the other end is provided with a hook 5 adapted to detachably engage the ring at a 70 point diametrically opposite to the point 3. In practice, I find it convenient to form this bail 4, by simply bending up one end of the wire forming the ring, the ring and bail thus being constructed from a single piece 75 of wire. Instead of forming the ring and bail integral as described, I may, if desired, form the bail separately, and secure its end within the coupling 6, or otherwise attach it to the ring. In any event, the bail is 80 permanently attached to the ring at a point immediately adjacent the break in the ring, or, in other words, adjacent the coupling 6.

7 designates the filter bag which may be 85 of any usual or desirable material. This bag is folded and sewed at its upper edge to provide a continuous loop 8, this loop being open at one point as indicated at 8^a in Fig. 3.

When it is desired to place the bag on the 90 holder, the free end 2 of the ring is inserted into the open end 8^a of the loop as shown in Fig. 3 and is then threaded entirely through the loop, the hook 5 being detached from the ring as shown in full lines in Fig. 95 1 to permit the bag loop to freely pass over the length of the ring.

After the bag is in position, the free end 2 of the ring is inserted in the coupling 6 as 100 shown in Fig. 2 and the hook 5 engaged with the ring 1 as indicated in dotted lines in Fig. 1.

It will thus be seen that I have provided a very practical and convenient filter bag 105 holder, which admits of the bag being quickly and easily removed and replaced when desired, and it is thought that the many advantages of my invention will be fully appreciated without further discussion.

110 What I claim is:—

1. A filter bag holder comprising a di-

- vided ring having separable ends, and a bail secured at one end to said ring at one point, and provided at its other end with means by which it may be detachably engaged with said ring at another point, said ring being free from obstructions at all points except that at which it is secured to the bail.
2. A filter bag holder comprising a divided ring, means for uniting the ends of the ring, and a bail having one end rigidly secured to the ring at one point and having at its other end a hook adapted to detachably engage the ring at a diametrically opposite point.
3. A filter bag holder comprising a ring having a break at one point, and a bail secured at one end to the ring adjacent such

break, and having at its other end means for detachably engaging the ring at a diametrically opposite point.

4. A bag holder comprising a divided ring having a free end adapted to enter the loop around the edge of a bag and be threaded through said loop, and a bail having one end secured to the ring and the other end detachable therefrom so as to permit the ring to pass freely through the bag loop.

5. A filter bag holder comprising a divided ring and bail all formed from a single piece of wire, the bail at one end being integral with the ring, and at its other end having a hook adapted to detachably engage the ring.

In testimony whereof I affix my signature. 35
HENRY C. ARWE.
